Primary Examiner — Cynthia R Underwood(74) *Attorney, Agent, or Firm* — Nitin Kaushik(57) **CLAIM**

The ornamental design for a laptop case, as shown and described.

DESCRIPTION

FIG. 1 is a front, left and top perspective view of a laptop case, showing my design.

FIG. 2 is a rear, right and bottom perspective view thereof.

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof; and,

FIG. 9 is an enlarged view of portion 9 shown in FIG. 1. The broken lines in the drawings depict portions of the laptop case which form no part of the claimed design. The broken lines in Figures 1 and 9 forming the marker form no part of the claim.
